UNITED STATES PATENT OFFICE.

HENRY F. G. FUCHS, OF JERSEY CITY, NEW JERSEY.

DESIGN FOR A FLORAL LAPEL ORNAMENT.

SPECIFICATION forming part of Design No. 21,690, dated July 5, 1892.

Application filed March 31, 1892. Serial No. 427,282. Term of patent 3½ years.

To all whom it may concern:

Be it known that I, HENRY F. G. FUCHS, a citizen of the United States, residing at Jersey City, in the county of Hudson and State of New Jersey, have invented and produced a new and original Design for a Floral Lapel Ornament, of which the following is a specification, reference being had to the accompanying drawing, forming part thereof.

10 The figure is a front elevation of my design for a floral lapel ornament.

My design for a lapel ornament is in general outline a star-shaped flower.

15 The leading feature of my design consists of five or more leaves in the shape of elongated elipses somewhat pointed at the extremes and having corded edges, the leaves being grouped about a stem.

In the drawing, A is the stem, and B B the leaves, with corded edges *b b* grouped thereon. 20

My floral lapel ornament is a representation of silk and twisted wire. Each of the leaves B B has the appearance of silk spun from a center over a twisted wire, so representing a corded edge *b*. 25

What I claim, and desire to protect by Letters Patent, is—

The design for a floral lapel ornament, substantially as herein shown and described.

HENRY F. G. FUCHS.
